(57) **CLAIM**

The ornamental design for an electrical distribution board, as shown and described.

DESCRIPTION

FIG. 1 is a top, front, right perspective view of an electrical distribution board showing the new design;

FIG. 2 is a front view thereof;

FIG. 3 is a left view thereof;

FIG. 4 is a right view thereof;

FIG. 5 is a top view thereof;

FIG. 6 is a bottom view thereof; and,

FIG. 7 is another top, front, right perspective view thereof shown in an installed configuration.

The dashed lines shown in FIGS. 1-7 represent portions of the electrical distribution board that form no part of the claimed design and in FIG. 7 also represent unclaimed environment of a panel into which the electrical distribution board is installed. The electrical distribution board is shown in dash-dot lines with a symbolic break in its height. The appearance of any portion of the article between the break lines forms no part of the claimed design.
